UNITED STATES PATENT OFFICE.

HORACE S. PATTERSON, JR., OF LEWISPORT, KENTUCKY.

INTERLOCKING GUARD.

Application filed January 16, 1923. Serial No. 613,021.

To all whom it may concern:

Be it known that I, HORACE S. PATTERSON, Jr., a citizen of the United States, residing at Lewisport, in the county of Hancock and 5 State of Kentucky, have invented certain new and useful Improvements in an Interlocking Guard, of which the following is a specification.

This invention relates to mowing machines and the primary object of the invention is to provide an improved means for interlocking the guards of the finger bar together, so as to prevent movement of the guards in relation to one another and the 10 consequent working loose of the guards.

Another object of the invention is to provide novel means for connecting the guards of the mowing machine together in such a manner, that the guards will always be held 20 in correct alignment and prevented from moving in relation to one another, and thereby preventing the damaging of the guards caused by the guards vibrating against one another.

25 A further object of the invention is to provide a novel guard for mowing machines which can be readily connected or disconnected from the finger bar without disconnecting the other guards from the finger 30 bar, the guards carrying novel means for permitting the interconnection thereof.

A still further object of this invention is 35 to provide an improved interlocking guard for mowing machines of the above character, which will be durable and efficient in use, one which will be simple and easy to manufacture, and one which can be placed upon the market at a reasonable cost.

With these and other objects in view, the 40 invention consists in the novel construction, arrangement and formation of parts, as will be hereinafter more specifically described, claimed and illustrated in the accompanying drawings, in which—

45 Figure 1 is a fragmentary plan view of a finger bar of a mowing machine showing the improved guards connected therewith.

Figure 2 is a detail perspective view of one of the improved guards.

50 Figure 3 is a detail section taken on the line 3—3 of Figure 1.

Figure 4 is a detail perspective view showing the means of interlocking the guards together, and

55 Figure 5 is a detail view of a modified form of guard.

Referring to the drawings in detail, wherein similar reference characters designate corresponding parts throughout the several views, the letter A generally indicates a 60 finger bar of any preferred character and B the improved novel interlocking guards therefor.

The guards B are of the usual construction, and the inner terminals thereof are 65 provided with the offset attaching portions 10 for engaging the finger bar. Forwardly of the offset attaching portions 10 of the guards B, the same are provided with laterally extending arms 11 and 12. As shown 70 75 the arm 11 is provided with a depending offset portion 13, which is provided with a suitable opening or eye 14. The outer end of the arm 12 is provided with a hook 15, which is adapted to extend through the opening 14 formed in the depending offset extension 13 of the arm 11 of the adjacent guard, when the guards are in their assembled position on the finger bar A. As shown the bill 16 of the hook 15 is adapted 80 85 to engage the shoulder 17 formed by the depending offset extension 14 and this bill can be tapered if so desired in order to facilitate the insertion thereof through the opening 14.

In use of the improved guards the outermost guard B has the hook 15 thereof extended through a suitable opening formed in the outer shoe 19 of the cutter bar. The next adjacent guard B is then placed in 90 position and the hook 15 is inserted through the opening 14 of the guard already placed in position. The other guards are placed in position in the same manner, until the last guard is in place. This guard can be secured to the inner shoe 20, of the finger bar, by means of a suitable removable bolt or the like 21, which is extended through the opening 14. It is of course to be understood that the attaching portions 10 of the 100 guards B are secured by bolts 22 to the finger bar in the ordinary manner.

In Figures 1 to 3 inclusive I have shown the arms 11 and 12 formed integral with the guards, but it is to be understood that 105 the arms 11 and 12 can be formed separate from the guards and made of sheet metal or the like.

In Figure 5 of the drawings I have shown the modified form of guard, in which the 110 interlocking means is formed separate therefrom.

As shown in Figure 5 of the drawings the body portion 25 of the guard is provided with a longitudinally extending groove 26, and a transversely extending groove 27 at the inner terminal thereof. The interlocking means in this form is broadly designated by the reference character 28 and as shown includes a cross bar 29 having the central portion thereof provided with a forwardly projecting tongue 30 which is adapted to seat in the longitudinal groove 26 in the body portion 25 of the guard. The cross bar 29 of course seats in the cross or transverse groove 27 and can be secured thereto by means of a bolt or the like 31. The bar 29 projects equal distances from the opposite side of the body portion 25 of the guard and one end of the bar is provided with a depending offset extension 32, while the other end of the guard is provided with a hook 33. The offset extension 32 can be provided with a square opening 34 if so desired. The guards B in the modified form are connected together in the same manner as shown in Figure 1 of the drawings and function in the same way.

It is obvious that when the guards are constructed in accordance with this invention that the same will be firmly interlocked and that movement thereof will be absolutely precluded. This prevents the working loose of the guards and prevents the hammering of the guards against one another and thus saves the guards from becoming mutilated. Owing to the construction of the interlocking means, the guards can be easily removed from the finger bar A.

Changes in details may be made without departing from the spirit or the scope of this invention.

What I claim as new is:

1. The combination with a finger bar of a mowing machine, of a plurality of guards secured to the bar, eyes carried by one side of each guard, and hooks carried by the other side of each guard for engaging in said eyes.

2. As a new article of manufacture, a guard for cutter bars comprising a body, laterally extending arms carried by the opposite sides of the body, an eye carried by one end of one arm, and a hook carried by the outer end of the other arm.

3. As a new article of manufacture, a guard for cutter bars comprising a body, laterally extending arms carried by the body, a depending outwardly extending offset extension formed on the terminal of one arm and having an opening therein, and a hook formed on the terminal of the other arm.

4. The combination with a finger bar of a mowing machine, of a plurality of guards secured to the bar, laterally extending arms carried by the opposite sides of each guard, a laterally extending offset eye formed on the terminal of one arm, and a hook formed on the terminal of the other arm, the bill of the hook terminating in a plane below the upper face of the arm, the hooks of the guards being adapted to engage the eyes of the adjacent guards, the body of the eyes being adapted to engage the lower faces of the arms carrying the hooks, and the bills of the hooks being adapted to engage the arms carrying the eyes directly inward of said eyes.

In testimony whereof I affix my signature.

HORACE SMITH PATTERSON, JR.
